DESIGN FOR A DRESS

Beatrice Chudnoff Kalish, New York, N. Y.

Application April 30, 1938, Serial No. 76,889

Term of patent 3½ years

To all whom it may concern:

Be it known that I, Beatrice Chudnoff Kalish, a citizen of the United States of America, residing in city of New York, county of New York, and State of New York have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the inserted, alternating, colored bands on the skirt portion of the dress in combination with matching colored pockets and belt.

I claim:

The ornamental design for a dress substantially as shown and described.

BEATRICE CHUDNOFF KALISH.
